[57] **CLAIM**

The ornamental design for a portable tissue holder, as shown and described.

DESCRIPTION

FIG. 1 is a front elevational view of the portable tissue holder of the present invention;

FIG. 2 is a rear elevational view of the portable tissue holder of FIG. 1;

FIG. 3 is a left side elevational view of the portable tissue holder of FIG. 1;

FIG. 4 is a right side elevational view of the portable tissue holder of FIG. 1;

FIG. 5 is a top plan view of the portable tissue holder of FIG. 1;

FIG. 6 is a bottom plan view of the portable tissue holder of FIG. 1; and,

FIG. 7 is a top, front, right side perspective view of the portable tissue holder of FIG. 1.

The broken lines showing of a portable toilet and tissue paper in FIG. 7 is for illustrative purposes only and form no part of the claimed design.
